UNITED STATES PATENT OFFICE.

JULIUS P. HEIL, OF MILWAUKEE, WISCONSIN, ASSIGNOR TO THE HEIL CO., OF MILWAUKEE, WISCONSIN, A CORPORATION OF WISCONSIN.

MANHOLE COVER.

Application filed December 19, 1924. Serial No. 757,028.

This invention relates to improvements in manhole covers.

Tanks of many kinds and more particularly tanks mounted on motor trucks for carrying oil and gasoline are provided with compartments and each compartment is formed with a manhole opening closed by a cover which is usually threaded into the compartment of the tank. The tanks are usually mounted on wooden truck members and the truck members are supported upon wheels having pneumatic tires so that the tanks are insulated from the ground. Static electricity is oftentimes generated in the tank, and as this is hazardous due to the inflammable fluid carried in the compartments, it is customary to attach a short chain at one end to each tank and let the other end drag on the road to ground the tank and prevent the static electricity from igniting the gaseous vapors rising from the contents of the compartments.

It has been found in practice that the unscrewing and removal of a manhole cover will under certain conditions produce a static spark which is liable to ignite the contents of the tank.

It is one of the objects of the present invention to overcome the before mentioned objectionable feature and provide a construction in which this risk will be eliminated.

A further object of the invention is to provide a manhole constructed in a manner to eliminate the possibility of the cover becoming misplaced or lost when disengaged from its compartment.

A further object of the invention is to provide a manhole cover of simple construction, which is strong and durable and is well adapted for the purpose described.

With the above and other objects in view, the invention consists of the improved manhole cover and its parts and combinations as set forth in the claims and all equivalents thereof.

In the accompanying drawing in which the same reference characters indicate the same parts in all of the views:

Fig. 1 is a side view of a compartment tank provided with the improved manhole cover;

Fig. 2 is a vertical sectional view of the manhole cover and a portion of the tank taken on a larger scale; and

Fig. 3 is a top view thereof taken on a smaller scale.

Referring to the drawing, the numeral 5 indicates a tank of the compartment type which is usually mounted on motor trucks. Each compartment is formed with a manhole 6 closed by a cap 7 threaded into the manhole or opening 6 in any manner desired. For convenience in removing or replacing the cap 7 to clean out the compartment, lugs 8 are provided which project upwardly from the cap and are adapted to be engaged by a wrench or other tool, not shown. Each cap 7 is provided with a central threaded opening 9 for receiving a threaded cover 10 therein. Said cover is formed with an annular flange 11 to form a tight closure and also with projecting arms 12 to permit the easy removal of the cover without the use of tools. The cover is also provided with a central threaded opening 13 to receive a closure plug 14.

Immediately beneath the plug opening 13 the cover is provided with a downwardly extending loop or eye 14 to which is connected one end of a flexible contact member or chain 15. The other end of said contact member or chain is connected to the cap member 7 by an eyed member 15' so that when the cover is unscrewed and removed from the cap the cover will still be grounded to the tank by means of the chain and the liability of the creation of a static spark in separating the cover from the cap or tank will be eliminated. To prevent the turning of the cover from twisting the chain the said chain is provided with a turn buckle 16 forming part of the chain and which turn buckle is located immediately below the loop or eye 14. Attention is further directed to the fact that the chain also serves as a means for preventing the cover member from being lost or misplaced when unthreaded from the cap.

It will also be seen that the combination of the cap and cover provides a cover which may be easily removed to permit filling the tank or compartment and when it is desired to clean the tank, the larger cap may be removed.

From the foregoing description it will be seen that the manhole cover is of very simple construction and is well adapted for the purpose described.

What I claim as my invention is:

1. The combination with a metal tank for holding a volatile inflammable fluid and having a threaded opening, of a two-part closure

therefor, comprising a metal cap part threaded into said opening and forming an electrical connection with the tank and having a central threaded opening, a cover part threaded 5 into the cap part opening and having outwardly projecting arms for moving said cover part, the removal of the cap part permitting access to the interior of the tank, and a flexible contact member normally within the tank 10 and connected to the two parts of the closure to form an electrical connection between the two closure parts and to prevent the separation of said parts but permitting the separation of the two-part closure from the tank.

15 2. The combination with a metal tank for holding a volatile inflammable fluid and having a threaded opening, of a two-part closure therefor, comprising a metal cap part threaded into said opening and forming an electrical

connection with the tank and having a central 20 threaded opening, a cover part threaded into the cap part opening and having a central threaded opening and a loop beneath said opening, the removal of the cap alone permitting access to the interior of the tank, a plug 25 closing said central opening, said cover member having outwardly projecting arms for moving said cover part, and a metal chain normally within the tank and connected at one end to the loop and at its other end to 30 the cap part to form an electrical connection between the two closure parts and to prevent the separation of said parts but permitting the separation of the two part closure from the tank.

35 In testimony whereof, I affix my signature.

JULIUS P. HEIL.
